DESIGN FOR A TYPEWRITER BASE

Samuel I. Berger, Newark, N. J.

Application April 27, 1934, Serial No. 51,549

Term of patent 7 years

To all whom it may concern:

Be it known that I, SAMUEL I. BERGER, a citizen of the United States, residing in the city of Newark, county of Essex, and State of New Jersey, have invented a new, original, and ornamental Design for a Typewriter Base, of which the following is a specification, reference being had to the accompanying drawing, forming a part hereof.

In the drawing:

The figure represents a perspective view of a typewriter base, showing my new design.

I claim:

The ornamental design for a typewriter base, as shown.

SAMUEL I. BERGER.
